UNITED STATES PATENT OFFICE.

EDWIN C. WASHBURN, OF ENGLEWOOD, NEW JERSEY.

CASTING APPARATUS.

1,235,744.

Specification of Letters Patent.

Patented Aug. 7, 1917.

Application filed March 21, 1912. Serial No. 685,158.

To all whom it may concern:

Be it known that I, EDWIN C. WASHBURN, a citizen of the United States, residing at Englewood, in the county of Bergen and State of New Jersey, have invented certain new and useful Improvements in Casting Apparatus, of which the following is a full, clear, and exact description, such as will enable others skilled in the art to which it applies to make and use the same.

This invention relates to casting and with respect to its more specific features, to a casting apparatus adapted for use in casting of various kinds.

One of the objects of the invention is to provide a practical device of the kind described which shall insure a highly homogeneous product.

Another object of the invention is to provide a simple and efficient device of the kind described which shall substantially prevent piping and control any segregation in the resultant product.

Another object is to provide a practical and efficient vacuum heat-insulating device which may be readily applied to various molds.

Another object is to provide a practical and efficient process for casting materials whereby a highly useful product is obtained.

Other objects will be in part obvious and in part pointed out hereinafter.

The invention accordingly consists in the several features of construction, combinations of elements and arrangement of parts, which will be exemplified in the method hereinafter disclosed and the construction hereinafter set forth, and the scope of the application of each of which will be indicated in the following claims.

In the drawing, wherein is shown one of the possible embodiments of the invention,

Figure 1 represents a sectional side elevation taken on the line $x-x$ of Fig. 2, showing an ingot in position;

Fig. 2 represents a plan view of the device, parts being broken away to show the under structure.

Similar reference numerals refer to similar parts in both views of the drawing.

Referring now more particularly to the drawing, 1 represents an upright tubular chamber preferably of octagon shape in cross-section and provided with tapering

walls 2 on the inner periphery thereof. On the upper end of the chamber is a preferably removable heating-insulating device which comprises a substantially cylindrical casing 3, which is provided on its bottom face with an annular recess 4 which is situated adjacent the outer curved periphery of the casing. A corresponding annular recess 5 is formed in the upper end face of the tubular chamber and when the casing is placed in position the grooves 4 and 5 coincide. Sealing material such as moistened clay 6, or the like, is placed in the recess and serves to make a tight joint between the heat-insulating device and the tubular chamber.

The casing 3 comprises three concentric, spaced, annular, wall members, the outer annular member or ring designated as 7, the intermediate ring as 8 and the inner ring as 9. Each of these rings is tapered slightly from the bottom to the upper portion thereof. Between these rings are formed three concentric chambers, the outer chamber being designated as 10, the intermediate as 11 and the inner as 12. The chamber 10 is preferably non-communicative with the chambers 11 and 12 and its outer wall forms the outer wall of the casing. Chambers 11 and 12 are, however, adapted to communicate with each other to form thereby suitable passageways as will be hereinafter described. Passageway 11 is provided with two preferably diametrically opposite radial channels 13 and 14 which are disposed substantially at right angles to the passageway 11 and which pass through the walls 7 and 8 adjacent the bottom of the casing.

The chamber 10 is preferably evacuated and thereby forms a highly efficient and practical heat-insulating portion adjacent the outer periphery of the casing. The passageway 12 is preferably of greater area than either of the other chambers 10 and 11 and is substantially cylindrical in outline as opposed to the chambers 10 and 11, which are, as shown in this embodiment, annular.

When in position the passageway 12 is adapted to communicate with the interior of the chamber 1.

A cap 15 is adapted to be placed upon the upper end face of the casing 3, and its outer periphery preferably lies within the outer periphery of the casing, and in this embodiment over-spreads the passageways 11 and

12. Its outer edge rests on the face of the casing immediately above the intermediate wall 8.

The cap as shown is removable from the remainder of the casing and is provided with a removable cover 16 which is approximately centrally disposed and is provided with a handle 17. The cover is adapted to close the upper end of a substantially centrally disposed cylindrical open-ended chamber 18 provided with downwardly tapering walls and passing through the top and bottom surface of the cap. The lower orifice 19 of this cylindrical chamber is in communication with the passageway 12 in the casing when the cap is in proper position upon the end of the casing.

Passing through the cap in substantially radial lines are preferably cylindrical channels 20 spaced about the cap. These passageways originate at and communicate with the inner cylindrical chamber 18 and conforming in general outline to the outer periphery of the cap they emerge in the lower face thereof at orifices 21. These orifices when the cap is positioned on the end of the casing are adapted to register and communicate with substantially cylindrical ducts 22 which are substantially vertically disposed and pass into various parts of the chamber 11, through the upper wall thereof, thus providing communication between passageways 11 and 12 through channel 20 and cylindrical chamber 18.

35. In normal use the passageway 11, which adjoins the evacuated chamber 10, is adapted to contain heating gases and to permit their circulation therethrough and their discharge into the open air through the channels 13 and 14, thus providing an insulating belt of heated gases. The inner wall 9, which adjoins the passageway 11, also acts as a heat-insulating member being composed of a refractory material, preferably baked sand, and the sand is adapted to be held in place by a surrounding annular casing 23, preferably of iron, which is provided with a bulge 24. This bulge is adapted to aid in holding the sand in position. The inner periphery of the wall 9 is preferably provided with a coating of carbonaceous material, preferably graphite 25.

The wall 9 is of less depth than the other two walls 7 and 8, thereby providing a shoulder 26 which is adapted to receive an annular plate 27 of clay or other refractory material resting upon the upper face of the chamber 1. The plate 27 is provided with a flared aperture 28 which is of slightly less diameter than the passageway 12 and is adapted to guide material into chamber 1. Carbon, graphite or similar substances 29 may be sprinkled about the junction of the plate 27 and the wall 9.

65. In the use of the apparatus the heat-insu-

lating device is grasped by the handles 30 provided on either side of the casing and placed in position upon the top face of the chamber 1, the recesses 4 and 5 having been previously luted. The cap 16 is then removed from the casing and molten material such as steel or other metal to be used in casting is poured into the chamber 1 through the passageway 12, being guided in its direction by means of the aperture 28 in the plate 27 in such manner that there is little, if any, contact of the metal stream with the sides of the chamber. The tapered casing having been substantially filled with metal up to the upper end face of the wall 9, the cap is placed in position upon the end of the casing, the cover is removed and a suitable quantity of graphite or other similar material 31 is placed on the upper face of the metal about the orifice 19. The cover 35 is then replaced and the metal allowed to cool. The graphite 29 and 31 will burn, thereby heating the metal in contact therewith and serving as heat insulators therefor, and evolve gases which will pass upward through the channels 20 and passageway 11, thus passing about the upper portion of the metal and through the channels 13 and 14 to the outer air. Also any gases passing from the metal will follow this 95 same course and thus a flow of heating medium will be provided through the passageway 11, serving as a heat-insulating blanket. It is to be noted that it is preferable to use a quiet steel in using the carbonaceous 100 material in order that there may be no boiling or movement to displace the carbonaceous material. A quiet steel may be produced by addition of silicon or other similar material to the steel.

105. During the cooling of the metal there will be a tendency of the outer parts of the material being cast and those parts exposed to mediums which in themselves are not heat-insulating to cool more quickly than the inner portions of the material and those portions which are surrounded by heat-insulating devices. On account of the heat-insulating members, including the evacuated chamber, the passageway for heating gases 115 which are evolved from the metal and the refractory member, which are about the upper end of the metal in the passageway 12, the rate of radiation from this portion of the metal will be very small, in fact, almost 120 negligible, so that there will be a tendency to preserve the temperature of this metal at a point substantially higher than the temperature of other parts of the metal. By thus keeping the upper portion of the metal 125 hot as the central portions below it cool, there will be a tendency in the particles of the metal to work downwardly and as this action takes place there will be a continuous feed of heated metal from the chamber 12 130

and the whole interior portion of the ingot will cool substantially uniformly and in such manner that there will be a substantially equal contraction therethrough. In this way 5 the undesirable phenomena of piping and other evils due to similar causes will be substantially overcome. For example, in the casting of steel ingots there is a tendency to segregation of impurities such as slag, 10 phosphorus, silicon and sulphur, which segregations are most undesirable and tend to follow the line of slowest cooling.

By means of the present apparatus it is found that these segregations gradually 15 work themselves to the top of the metal and collect in that portion thereof adjacent the heat-insulating device. The resultant product instead of showing pipes and segregations will have only a small cupped neck 20 portion in which most of the impurities are segregated and which may be broken off with very little loss of metal.

In actual practice ingots have been obtained in which the proportion of metal 25 forming the cup, including impurities, is very small and in these ingots piping is practically absent. After the metal has cooled the heat-insulating device may be removed therefrom by lifting it by means of 30 the handles and the apparatus may then be set up for use upon another molding device.

It is to be noted in accordance with the above construction that there will be substantially no flaking on the sides of the finished 35 ingot or other casting in view of the fact that the metal in being poured into the chamber 1 is guided by means of the plate 27 and since the stream does not contact with the sides, substantially no opportunity 40 is given for sudden cooling of small quantities of metal on the sides with resultant flake.

It is to be understood that the term "casting" is herein employed in its broad sense 45 as indicating the treatment of molten material by means of suitable devices to give it a desired shape. It will thus be seen that according to the above, the objects enumerated, among others, are completely and conclusively fulfilled.

As many changes could be made in carrying out the above method, and in the above construction, and many apparently widely different embodiments of this invention 55 could be made without departing from the scope thereof, it is intended that all matter contained in the above description or shown in the accompanying drawing shall be interpreted as illustrative and not in a limiting 60 sense.

It is also to be understood that the language used in the following claims is intended to cover all of the generic and specific features of the invention herein described and all statements of the scope of the 65

invention, which, as a matter of language, might be said to fall therebetween.

Having described my invention, what I claim as new and desire to secure by Letters Patent is:

1. A casting device, including a molding chamber and a heat insulating device comprising an inner chamber and a passageway situated next thereto and adapted to receive heating gases from said inner chamber. 70

2. A casting device, including a molding chamber and a heat insulating device comprising an inner chamber and an outer chamber, said inner chamber being adapted to communicate with said outer chamber, 80 and means adapted to generate heating gases in said inner chamber, said gases being adapted to pass into said outer chamber to thereby form an insulating medium about said inner chamber. 85

3. A casting device, including a molding chamber and a heat insulating device comprising a casing provided with an inner chamber, an intermediate chamber and an outer chamber, means adapted to guide a 90 heating medium from said inner chamber into said intermediate chamber, and means adapted to generate heat in said inner chamber, said outer chamber being evacuated.

4. A casting device comprising a chamber 95 and a heat insulating device comprising a plurality of chambers providing an evacuated portion and adapted to permit the circulation of a heating medium therethrough.

5. A casting device, comprising a tubular chamber, an annular insulating refractory member about one end of said chamber, a passageway adapted to permit the passage of a heating medium therethrough, said passageway adjoining said member, and carbonaceous material adapted to provide heating gases within said tubular chamber, said gases being adapted to flow through said passageway about said refractory member. 100 105

6. A casting device comprising an upright 110 tubular member having a heat insulating device composing one end thereof, said device including an inner annular refractory member, an outer annular member concentric therewith and forming a passageway between said refractory member and itself and a removable cap provided with a channel adapted to furnish communication with said passageway.

7. A casting device comprising a passageway thereabout adapted to permit the flow of a heating medium therethrough and an evacuated portion. 120

8. A casting device comprising a chamber, an annular evacuated chamber about said 125 first chamber and a passageway adapted to permit the flow of a heating medium therethrough, said passageway adjoining said second chamber.

9. A casting device comprising an up- 130

- right tubular chamber having a heat-insulating device at the upper end thereof, said heat insulating device including a casing providing an annular passageway adapted 5 to permit the flow of heating gases therethrough and an annular evacuated chamber, said chamber being concentric with and adjoining said passageway.
10. A casting device comprising a chamber, a refractory insulating member thereabout and a casing providing an evacuated chamber thereabout.
11. A casting device comprising a refractory insulating portion, a passageway adapted 15 to permit the circulation of gases therethrough and an evacuated portion.
12. A casting device comprising a chamber, a refractory insulating member thereabout, a passageway adapted to permit the 20 circulation of a heating medium therethrough, said passageway surrounding said refractory member and an evacuated chamber surrounding said refractory member and said passageway.
- 25 13. A casting device comprising an upright tubular chamber and a heat insulating device forming one end thereof, said heat-insulating device including a casing, an annular refractory insulating member with- 30 in said casing, an annular evacuated chamber having one wall thereof forming the outer wall of said casing, a passageway formed between the outer wall of said refractory member and the inner wall of said
- 35 evacuated chamber, said passageway being provided with a portion communicating with the outside air, and a cap forming the upper portion of said casing and overspreading said refractory member and said 40 passageway, said cap being provided with a channel communicating with said passageway, an orifice communicating with said channel and leading into said chamber and a removable cover adapted to permit entrance to said cap.
- 45 14. A casting device comprising a chamber, a heat insulating device located at one end thereof, said heat insulating device including a casing provided with three annular concentric walls spaced to provide an inner passageway and an outer inclosed chamber therebetween, the inner of said annular walls being composed of a refractory insulating material coated on its inner 50 periphery with carbonaceous material and lined on its outer periphery with metallic material, said inner wall being provided with a bulged portion adapted to aid in supporting said refractory member, said inner
- 55 passageway being provided with an opening communicating with the outside air and adapted to permit the circulation of heating gases therethrough, said outer inclosed chamber being evacuated, and a refractory 60 plate provided with an opening adapted to
- direct material into said first chamber, said plate being disposed between the bottom of said casing and the end of said first chamber.
15. A casting device comprising a molding chamber and a removable heat-insulating device, said heat-insulating device comprising a substantially cylindrical casing provided with a removable cap, said cap being provided with a removable cover, and 70 said casing including a plurality of passageways.
16. A casting device comprising an upright molding chamber and a removable heat insulating device including a casing 75 having three concentric rings providing a passageway and a chamber therebetween, said passageway being adapted to permit the circulation of the heating medium therethrough, said chamber being evacuated, a removable cap overspreading the inner one of 80 said annular members and said passageway, said cap being provided with a channel passing therethrough communicating with said passageway, an orifice adapted to communicate with said molding chamber and with said channel and a removable cover in alignment with said orifice, and a recess on the bottom face of said casing adjacent the outer wall thereof, said recess being adapted 85 to register with a corresponding recess on the upper face of said molding chamber, said recesses being provided with a sealing material resting therein.
17. A heat insulating device comprising 90 a refractory member, a passageway adapted to permit the circulation of a heating medium therethrough and an evacuated portion.
18. A heat insulating device comprising a 95 casing including a plurality of annular rings providing a plurality of chambers therebetween, one of said rings being composed of refractory material, two of said chambers communicating with each other, the other of said chambers being evacuated.
19. A heat insulating device comprising 100 a casing provided with three concentric spaced annular members forming a plurality of chambers therebetween, the inner 105 of said members being composed of refractory material coated on its inner periphery with carbonaceous material and provided with a casing of metallic material on its outer periphery, said refractory member being provided with a bulged portion, one of said chambers being adapted to permit the flow of a heating medium therethrough and communicating with another of said chambers and with the outside air and another 110 of said chambers being evacuated.
20. A heat insulating device comprising 115 a casing provided with a plurality of annular members providing passageways therebetween and a removable cap for said 120
- 125
- 130

casing provided with a removable cover, an orifice in alinement therewith and a channel communicating with said orifice, said orifice communicating with one of said passageways and with said channel, said cap being so positioned upon said casing that said channel communicates with another of said passageways, said last mentioned passageway being provided with communication with the outside air.

21. A molding device comprising a molding chamber and a heat insulating device

associated therewith, said heat insulating device comprising a plurality of spaced walls and a cap forming one end thereof, said cap being provided with a passageway adapted to provide communication between the spaces provided between said walls.

In testimony whereof I affix my signature, in the presence of two witnesses.
